UNITED STATES PATENT OFFICE.

CHAUNCEY MANLEY RATHBUN, OF FREDONIA, NEW YORK.

MUCILAGE-BOTTLE.

SPECIFICATION forming part of Letters Patent No. 576,150, dated February 2, 1897.

Application filed June 25, 1896. Serial No. 596,921. (No model.)

To all whom it may concern:

Be it known that I, CHAUNCEY MANLEY RATHBUN, a citizen of the United States, and a resident of Fredonia, in the county of Chautauqua and State of New York, have invented certain new and useful Improvements in Mucilage-Bottles, of which the following is a specification, reference being had to the accompanying drawings, forming a part thereof, in which similar letters of reference indicate corresponding parts wherever found throughout both views.

This invention relates to mucilage-bottles; and the object thereof is to provide an improved device of this class which is simple in construction and operation; a further object being to provide improved means for applying mucilage to paper or other material.

The invention is fully disclosed in the following specification, of which the accompanying drawings form a part, in which—

Figure 1 is a sectional view of a mucilage-bottle provided with my improved mucilage-applying device, and Fig. 2 a central longitudinal section of said device.

In the practice of my invention I provide a mucilage-bottle A, which may be of any desired form and which is provided with a neck a, and I also provide a mucilage-applying device or brush which consists of a plug B, which is adapted to serve as a stopper for the neck of the bottle, and said plug is provided at its upper end with a head b, which is adapted to serve as a handle, and at its lower end with an extension D, which is wedge-shaped in form and which is divided or slotted longi-

tudinally thereof at its lower end, the slit d extending upwardly almost the full length of the extension D. The plug B, the head b thereof, and the extension D are formed integrally and preferably composed of soft rubber, and the wedge-shaped extension D constitutes an effective brush for applying mucilage. The lower end of the extension D may be as wide as the neck of the bottle, if desired, and said extension is preferably made of such length as to extend nearly to the bottom thereof.

This device is simple in construction and operation, and is preferably adapted to accomplish the result for which it is intended, while being also comparatively inexpensive; and,

Having fully described my invention, I claim as new and desire to secure by Letters Patent—

The combination with a mucilage-bottle, of a stopper composed of soft rubber, said stopper being provided with a head, which is adapted to serve as a handle, and the lower end thereof, being extended, and wedge-shaped in form, said extended end being also divided or slotted, substantially as shown and described.

In testimony that I claim the foregoing as my invention I have signed my name, in presence of the subscribing witnesses, this 22d day of June, 1896.

CHAUNCEY MANLEY RATHBUN.
